F. BENDIX

LATCH

Filed Aug. 5, 1924

INVENTOR
FREDERICK BENDIX.
BY *John L. Sibley*.
ATTY.

UNITED STATES PATENT OFFICE.

FREDERICK BENDIX, OF SAN FRANCISCO, CALIFORNIA.

LATCH.

Application filed August 5, 1924. Serial No. 730,223.

To all whom it may concern:

Be it known that I, FREDERICK BENDIX, a citizen of the United States, residing in the city and county of San Francisco and State 5 of California, have invented a new and useful Improvement in a Latch, of which the following is a specification.

My invention relates to securing means for cupboard doors and the like wherein doors are mounted in pairs hinged at opposite edges and having their adjacent edges in proximate relation, and particularly to an improved latch actuated by the movement of one of the doors to secure or release both of a pair of such doors.

The primary object of my invention is to provide an improved latch for cupboard doors and the like.

Another object is to provide an improved 20 latch which will effectively retain both of a pair of doors in closed position.

A further object is to provide an improved latch which is actuated by the inward movement of one of a pair of doors to closed position to secure both the doors, and actuated by the outward movement of said doors to release both of said doors thereby facilitating the fastening and releasing of the doors.

Another object is to provide an improved 30 latch which is normally actuated by the movement of an opposite door but which may be operated independently to secure the door upon which it is secured without interfering with the normal engagement by the opposite door.

A still further object is to provide an improved device which may be mounted at the top of relatively high doors such as cannot be readily secured by manually operated latches.

A still further object is to provide an improved latch which is simple and easily applied and which will form a cheap and efficient means for securing cupboard doors and the like.

I accomplish these and other objects by means of the device disclosed in the drawings forming a part of the present specification wherein like characters of reference are used to designate similar parts throughout said specification and drawings and in which,—

Fig. 1 is a plan view of the latch as applied upon a pair of cupboard doors.

Fig. 2 is a right side elevation of the latch as shown in Fig. 1.

Fig. 3 is a sectional detail showing the manner in which the latch engaging member is moved into engagement with the latch when in the latching position.

Referring to the drawings, the numerals 1 and 2 are used to designate in general pair of doors such as commonly used upon cupboards and the like wherein doors are mounted in pairs hinged upon opposite edges and 65 having their adjacent edges arranged in proximate relation. One of the doors is preferably provided with an extension 3 adapted to be received within a notch 4 formed upon the opposite door.

Upon one of the doors is secured a latch, designated in general by the numeral 6, pivotally mounted upon a mounting member 7 screwed or otherwise secured upon the inner side of the free edge of the door. The latch 75 6 is provided with a hook shaped portion 8 and a laterally disposed extension 9 arranged opposite the hook portion 9. The latch is preferably mounted upon a pin 12 extending between extensions 13 formed upon the mounting member 7, whereby a staple bearing is obtained.

A latch engaging member 14 is screwed or otherwise secured upon the door opposite the latch 6, said member having a lateral 85 extension 16 terminating in an inwardly turned lip 17. A pin 18 is slidably mounted upon the latch 6 adjacent the end of the extension 9, and arranged to be engaged by the lip 17 when the doors are moved to a closed 90 position as hereinafter more fully explained.

A retaining member 19 is secured adjacent the latch 6 in a position adapted to be engaged by the hook portion 8 of the latch 6 when in latching position, said member 95 preferably consisting of a sleeve held by a screw 21 secured in the top of the cupboard 23 or other convenient mounting such as a shelf within the cupboard.

The extension 8 extends past the edge of 100 the door 1 upon which it is mounted and overhangs the opposite door 2 sufficiently to cause the pin 18 to be engaged by the lip 17 of the member 14, said extension being made substantially L shaped so that when the latch 105 is moved about its pivot mounting the extension will fit around the edge of the door. The body portion of the latch 6 is provided with a pointed end 21 adapted to engage the mounting member 7 to limit the movement of the latch relative to the mounting. 110

In operation the several members are

mounted in the relation shown in the drawings. When now the doors are moved to closed position the edge of door 2 engages the end of the extension 8 and moves 5 the latch pivotally about its mounting pin 12. As the doors approach the fully closed position the hook portion 8 of the latch moves into engagement with the retaining member 19 as shown in full lines in Fig. 1 10 of the drawings. At the same time the pin 18 moves to a position immediately inside the edge of the lip 17 of the latch engaging member 14 so that when the doors reach the fully closed position door 1 will be held in 15 position by the hook 8 and door 2 will be held by engagement between the lip 17 and the pin 18, both doors being thus fastened in the closed position.

When now it is desired to open the doors, 20 the door 1 is swung outwardly about its hinges by means of a knob 22 or other suitable member adapted to be grasped by the hand of a person, sufficient pull being exerted to overcome the normal frictional resistance and causing the lip 17, engaging the latch through the pin 18, to swing the latch pivotally about its mounting and release the hook portion 8 from engagement with the retaining member 19. As the latch moves 25 away from the latching position shown in full lines, the pin 18 is moved out of the path of the lip 17 thus permitting the door 2 to be freely opened after the latch has been moved to the releasing position shown 30 in dotted lines in Fig. 1 of the drawings. As the latch has been thus released the door 1 may be freely opened if desired or allowed to remain in normal closed position. When the door 1 is again closed the latch will be 35 moved from the position shown in dotted lines to the latching position shown in full lines as above explained.

Should the latch be moved manually to cause the hook portion 8 to engage the retaining member 19 while the door is open, the lip 17 will be moved into engagement with the pin 18 when the door 2 is closed. To permit the door to be fully closed and the member 14 to enter normal engagement with 40 the latch, the pin 18 is afforded sufficient sliding movement to permit it to be raised while the lip 17 passes thereunder, the lower end of the pin 18 being lifted by the inclined back of the lip 17 until the lip has passed 45 under the pin, said pin thereafter dropping back to normal position. In this manner the member 14 is permitted to engage the latch whether said latch is in latching or releasing position, and operative fastening 50 engagement will be obtained between the several members regardless of the position of the latch when the closing of the doors is started. In this connection, it is important to note the pivotal movement of the latch 55 6 is limited by the pointed end 21 so that the

latch 6 cannot be swung inwardly so far as to prevent the hook portion 8 from engaging the member 19 when the doors are closed, the inclined edge 23 being formed upon the end of the hook portion 8 so that should the latch be moved to latching position while the door 1 is open the latch will be forced back to releasing position by the member 19 when the door is closed.

My improved latch is particularly valuable for use in cupboards, lockers and the like having tall doors such that the ordinary manually operated latch cannot be readily reached when placed at the top of the locker and where shelves are not available in lower 80 and more accessible position. As my device is operated entirely automatically by the opening and closing of the doors the device may be placed in elevated position without 85 inconvenience to the person opening or fastening the doors. Furthermore, being placed preferably at the extreme top of the door, the device will be very inconspicuous and will not interfere in any manner with the 90 storing of goods or the like within the cupboard.

Having thus described my invention what I claim as new and desire to secure by Letters Patent is,

1. A latch for cupboard doors and the like of the character described comprising a latch pivotally mounted upon one of a pair of doors hingedly mounted at opposite edges and having their adjacent edges in proximate relation, said latch being provided with an extension adapted to be engaged by the opposite door and moved thereby to latching position when the doors are moved to closed position; and means mounted adjacent the doors adapted to be engaged by the latch to retain the doors in said closed position.

2. A latch for cupboard doors and the like of the character described comprising a latch pivotally mounted upon one of a pair of doors hingedly mounted at opposite edges thereof and having their adjacent edges in proximate relation, said latch being provided with a hook portion and an extension adapted to be engaged by the opposite door and moved thereby to latching position when the doors are moved to closed position; a retaining member mounted adjacent the doors and adapted to be engaged by the hook portion of the latch when in latching position; and means mounted upon the door opposite the latch and adapted to engage the extension upon said latch to normally hold said door in closed position and to move the latch to releasing position when said door is opened.

3. A latch for cupboard doors and the like of the character described comprising a latch pivotally mounted upon one of a pair of doors hingedly mounted at oppo-

site edges thereof and having their adjacent edges in proximate relation, said latch being provided with a hook portion and an extension adapted to be engaged by the opposite door and moved thereby to latching position when the doors are moved to a closed position; a retaining member mounted adjacent the doors and adapted to be engaged by the hook portion of the latch when in latching position; a pin slidably mounted upon the extension; and a latch engaging member mounted upon the door opposite the latch and arranged to engage the pin carried by the extension to normally hold said door in closed position and adapted to move the latch pivotally to release the retaining member when said door is opened.

4. A latch for cupboard doors and the like of the character described comprising a latch pivotally mounted upon one of a pair of doors hingedly mounted at opposite edges thereof and having their adjacent edges in proximate relation, said latch being provided with a hook shaped latch

portion and a lateral extension arranged 25 opposite the hook portion and adapted to be engaged by the opposite door for moving the latch to latching position when the doors are moved to closed position; a retaining member mounted adjacent the doors and 30 adapted to be engaged by the hook portion of the latch; a pin slidably mounted adjacent the end of the extension; and a latch engaging member secured upon the door opposite the latch and provided with an inwardly inclined lip adapted to be moved under the pin when the door is moved to a closed position, said lip being adapted to engage the pin and normally hold the door 35 in closed position and to move the latch to 40 releasing position when the door is opened, the pin being moved out of the path of the lip as the latch is moved pivotally to releasing position.

In witness whereof I hereunto set my 45 signature.

FREDERICK BENDIX.
